Term of patent 14 years

(Cl. D24—1)

FIG. 1.

FIG. 2.

FIG. 4.

FIG. 1 is a perspective view of a dental instrument console showing my new design;

FIG. 2 is a front elevation thereof;

FIG. 3 is a side elevation thereof as seen from the left of FIG. 2;

FIG. 4 is a top plan view thereof, on an enlarged scale; and

FIG. 5 is a side elevation thereof as seen from the right side of FIG. 2.

The dominant features of the design reside in the portions shown in full lines.

The rear elevation, not shown, is substantially plain and unornamented.

I claim:

The ornamental design for a dental instrument console, as shown and described.
